UNITED STATES PATENT OFFICE.

CHARLES AUGUST LUNDGREN, OF DETROIT, MICHIGAN, ASSIGNOR TO BURROUGHS ADDING MACHINE COMPANY, OF DETROIT, MICHIGAN, A CORPORATION OF MICHIGAN.

ELECTRIC FOOT-SWITCH.

1,031,191.

Specification of Letters Patent.

Patented July 2, 1912.

Application filed September 19, 1910. Serial No. 582,676.

To all whom it may concern:

Be it known that I, CHARLES AUGUST LUNDGREN, a citizen of the United States, residing at Detroit, in the county of Wayne and State of Michigan, have invented certain new and useful Improvements in Electric Foot-Switches, of which the following is a specification.

The invention relates to foot switches such as employed for the turning on and off of an electric current in the operation of motor equipped adding machines, and the object is to improve the construction of such a device so as to make it highly practical in the matter of form and arrangement of parts and immunity from derangement or deterioration in use.

It will be understood that the general purpose of such a device as that upon which I seek to improve is to not only effectively close the circuit upon depression of a foot-piece or treadle but to maintain full contact of electrodes notwithstanding there may be slight relaxation of foot pressure, while at the same time the switch will open upon release of the foot-piece or treadle.

In the drawings which accompany and form part of this specification, Figure 1 represents the switch of my invention in perspective and in an open condition; Fig. 2 is a side elevation of a portion of the construction illustrating a changed relation as compared with Fig. 1, to wit, that which obtains when the switch is closed; Fig. 3 is a cross section on the line 3—3 of Fig. 1 and including an inclosing casing.

The reference numeral 2 designates a baseboard of insulating material which is mounted upon and secured to metal base block or plate 3 and the reference numeral 4 designates upright end plates secured to the baseboard or plate and one having a bushing 5 through which a cable 6 is introduced containing wiring, and the other having an opening 7 extending upward a considerable distance to accommodate the foot lever 8. The latter is pivoted in a bifurcated block 9^a secured to the baseboard 2 and base plate 3 and curves downward extending through a cut back portion 9 of the baseboard 2 and a similar cut back portion of the base plate 3 and thence out through the opening 7 beyond which it takes the form of a foot-switch or treadle 10. An expansion spring

11 is interposed between the baseboard and 55 said lever on the forward side of the latter's pivot thus tending to elevate the foot-switch or treadle. There is pivoted to another bifurcated block or post 12 a switch lever composed of a body portion 13 of insulating material and metal blades 14, said 60 12 being secured to the base plate by a screw 14^a, Fig. 3, entered through said plate and the insulating baseboard 2. The said switch lever is normally drawn downward 65 as to its forward end by a contractile spring 15 and has a stud 16 projecting from one side over a laterally-bent or offset portion of the rear arm 8^a of the lever 8. Obviously depression of the treadle 10 rocks the lever 70 13 lowering its blades 14. The latter are adapted to enter contact clips 16^a secured to conductor blocks 17 mounted on the base plate 2 and having binding posts 18 to which the wires of the cable 6 are attached. 75 Such rocking of said lever 8 is limited by its contact with a stud or post 19 rising from the baseboard. The lever 8 is limited as to normal position by contact of a lateral stud 20 with one side of the post 9^a. 80

There is mounted upon the baseboard 2 and secured to it and the base plate 3 a third bifurcated post or block 21 in which is pivoted a latch 22 of bell crank form. The upstanding portion of said latch has a 85 catch shoulder 23 upwardly beyond a beveled edge 24 and there is a guard portion 25 projecting beyond said catch shoulder. The stud 26 projects over the switch lever on the side opposite that from which the stud 16 90 projects and may in fact be integral with the latter, said stud 26 normally being in the plane below the catch shoulder 24. The studs 16 and 26 will preferably carry rollers for anti-friction purposes. An expansion 95 spring 30 between the baseboard 2 and the forwardly extending branch of the bell crank latch 22 tends to elevate said branch and swing the other branch rearward, but is normally restrained by reason of engagement between the rear arm 8^a of the foot lever 8 and a stud 31 projecting laterally from said forward branch of the bell crank latch, the stud being preferably roller-equipped. Upon depression of the treadle 100 10 pressure on said stud 31 is relieved so that the bell crank latch may rock under action of its spring 30 and the beveled edge 24 be

carried into the path of the stud 26 on the switch lever which lever is of course rocking at the same time. The continued rocking of said lever causes said stud to act 5 against the inclined edge 24 and slightly displace the latch against the stress of its spring 30, until the stud passes the shoulder 23, whereupon the spring 30 expands and causes the shoulder 23 to spring under and 10 cam the said stud upwardly, as illustrated in Fig. 2. Thus the switch lever is given impetus at this period and closes with a snap, the contact plates 14 striking against the limit post 19 as they engage the terminal clips 16. The lever is of course locked down by the shoulder 23 under the stud 26. This extreme depression of the treadle carries its rear arm slightly above the stud 31 and as in addition to this some degree of 15 movement of the catch is necessary before its shoulder becomes disengaged from the stud 26, it is obvious that a certain amount of play of the foot-lever is permissible without the switch being unlocked. At the same 20 time release of the treadle or foot lever will result in the unlocking of the switch lever and its springing to open position.

It will be understood that the foot lever spring 11 is superior in strength to the latch 30 spring 30, and further, that the springing of switch lever to the open position produces a snap or report as the stud 16 lands against the rear arm of the treadle with considerable force. The switch lever spring 15 is 35 anchored at its lower end to a clip 40 held against the baseboard by the post 21.

It will be noted that the above described construction provides for a sort of alarm in the form of a snap, occurring as an incident 40 to the closing and opening of the switch. This serves to signify and emphasize the open or closed condition of switch to the operator. It further provides for closing and opening of the switch by a comparatively limited movement of the treadle and consequently the latter can occupy a position quite close to the floor on which the switch device rests. This contributes to the comfort of the user in that his foot does 45 not have to be held at a sharp angle or moved to any considerable extent in working the switch. It is obvious that the ob-

ject primarily stated is well fulfilled by the construction shown and described.

The parts are inclosed in a casing 50 55 which fits over the end plates 4 and against the side edges of the baseboard 2 and metal base plate 3 and is secured to the latter. It will be seen that the construction will thus be well protected from dust and dirt. 60

Having now described a manner of carrying out my invention, what I claim is:

1. In a foot switch, a suitable supporting base, a switch lever pivoted intermediate its ends on the base, a spring normally holding the switch lever open, a catch arranged to engage the rear end of the switch lever and hold it elevated, a foot lever adapted and arranged to engage the switch lever to close the switch when the treadle 70 is depressed and to engage the catch to release the switch lever when the treadle is released.

2. In a foot switch, the combination of a suitable supporting base, a foot lever pivoted thereto intermediate its ends and having a treadle at one end, a switch lever pivoted to the base intermediate its ends and having a portion overlying the inner arm of the foot lever and also having a catch stud, 80 and a latch of bell crank form pivoted to the base and having on one branch a shoulder to engage said catch stud and on the other branch a portion extending under the foot lever; the latter, the switch lever, 85 and the latch being spring-actuated.

3. In a foot switch, the combination of a suitable supporting base, a foot lever pivoted thereto intermediate its ends and having a projecting treadle portion, a switch 90 lever pivoted to the base and having a projecting stud extending over the inner arm of said foot lever and also having a catch stud, and a latch of bell crank form having a shoulder on one branch to engage said 95 catch stud and a stud on the other branch extending under the inner arm of the foot lever; the latter, the switch lever and the latch being spring-actuated.

CHARLES AUGUST LUNDGREN.
